UNITED STATES PATENT OFFICE.

HAROLD LEVY, OF NEW YORK, N. Y.

NOTE HOLDER.

1,405,850.

Specification of Letters Patent. Patented Feb. 7, 1922.

Application filed May 2, 1921. Serial No. 466,272.

To all whom it may concern:

Be it known that I, HAROLD LEVY, a subject of the King of Great Britain and Ireland, residing at New York city, in the 5 county of New York and State of New York, have invented certain new and useful Improvements in Note Holders, of which the following is a specification.

My invention relates to an improved note 10 holder and embodies what I believe to be an entirely new principle of operation in devices of this character.

The primary object of the invention is to provide a simply constructed device into 15 which objects such as banknotes, checks, bills and the like, either of uniform size or varying in size, may be quickly inserted, securely held and quickly removed. I am aware that efforts have been heretofore made to provide devices of this general character, but 20 all of these devices so far as I have been able to ascertain are defective in that they offer an obstruction to the ready insertion of the notes and the like, necessitating manipulation of some mechanical part of the structure to permit of such insertion or else such earlier devices are usable only where the 25 articles to be inserted are uniform in size.

The invention contemplates among other 30 features the provision of a holder for banknotes, checks, bills of exchange and similar articles particularly adapted for use by cashiers and persons handling such instruments, and may also be adapted for use in money 35 drawers.

The device is so arranged and constructed that individual as well as several articles such as checks, bills etc., not necessarily uniform in size may be quickly and conveniently 40 inserted and securely held.

In the further disclosure of the invention reference is to be had to the accompanying drawing, constituting a part of this 45 specification, in which similar characters of reference denote corresponding parts in all views, and in which.

Fig. 1 is a perspective view of the note holder partly filled; Fig. 2 is a side elevational view in part broken away showing the 50 capacity of the note holder.

Referring in detail to the drawing, I provide a table 10 made of wood or other suitable material, guards 11 set therein and rising perpendicularly therefrom and bent 55 horizontally so as to provide stops 11^a which limit the upward movement of plate 13

which is made of sheet metal or other suitable material and which plate 13 is pierced at 13^a so as to permit guards 11 to pass therethrough. Arms 15 depend from plate 13 by means of eye and loop 15^a and similar arms 16 are hooked into table 10 through eyes 10^a. Sleeves 17 are provided by means of which and within which are brought together the horizontal portions of arms 15 65 and 16. Coil springs 14 are wound around the outer surface of sleeves 17, one end of said coil spring 14 being fixed to arm 15, the other end of said coil spring 14 being fixed to arm 16. 70

In the use of the device when it is desired to insert the bills, notes etc., they are held flat one end in either hand and placed upon plate 13, a downward pressure being exerted on said notes etc. The inserts being flexible yield laterally as they pass stops 11^a. 75

When the articles being inserted have in this way been forced below stops 11^a and are again flat upon plate 13 the downward pressure on the articles is released and plate 13 80 with the bills etc., upon it is forced against the undersides of the stops 11^a by the upward pressure due to the extension of the coil springs, and the bills etc., are securely held in place. 85

Individual articles may be removed from the holder by drawing them from under stops 11^a one at a time toward either end. If desired the bills etc., may be removed in quantities. In this latter case slight downward pressure is exerted upon plate 13. 90

Having thus described my invention, I claim:

1. In a note holder the combination of a guide frame arranged to accommodate a 95 stack of unfolded currency notes, permitting free vertical movement of the stack of notes and permitting free longitudinal movement of the notes individually or collectively while confining said notes against 100 lateral movement, a deppressible member for resiliently supporting said stack and a pair of stop members overlying side margins only of said notes whereby the notes may be inserted unobstructively from above. 105

2. In a note holder the combination of spaced guide members for receiving therebetween a stack of currency notes, said guide members permitting vertical movement of the stack and also permitting free and unobstructed endwise or longitudinal removal of the notes from between said guide mem- 110

bers, a plate for supporting said stack of notes and also vertically movable between said guide members, resilient means tending to elevate said plate and the stack of notes supported thereby and stop members respectively overlying opposite side margins of the stack for resisting upward movement of the latter while permitting unobstructed insertion of notes from above.

10 3. In a note holder the combination of spaced guide members for receiving therebetween a stack of currency notes, said guide members permitting vertical movement of the stack and also permitting free and unobstructed endwise or longitudinal removal of the notes from between said guide members, a plate for supporting said stack of notes and also vertically movable between said guide members, resilient means tending to elevate said plate and the stack of notes supported thereby and stop members respectively overlying opposite side margins of the stack for resisting upward movement of the latter while permitting unobstructed insertion of notes from above, by merely locating the notes in superposed relation over the stack and pushing same downwardly by

pressure upon the top note in a zone extending along the note and intermediate said stops, whereby the margins of said notes will snap past the said stops upon depression of said resilient plate.

4. In a note holder the combination of a base, two pairs of spaced rods perpendicular to said base and forming guides for locating a stack of currency notes inserted between said pairs of rods, a plate located between said rod pairs and movable perpendicular to said base but limited by said guide rods against other movement, resilient means for forcing said plate away from said base and members respectively carried by said rod pairs and extending over the stack a limited distance from the side edges thereof, but extending longitudinally a substantial distance along the stack for limiting the perpendicular movement of the stack due to said plate while permitting substantially free insertion of notes between said guide rods.

In testimony whereof I have affixed my signature.

HAROLD LEVY.
